UNITED STATES PATENT OFFICE.

FRED A. DENNETT, OF SHEBOYGAN, WISCONSIN.

DESIGN FOR A VENEER-PRESSING MEMBER.

SPECIFICATION forming part of Design No. 33,967, dated January 22, 1901.

Application filed December 7, 1900. Serial No. 39,104. Term of patent 14 years.

To all whom it may concern:

Be it known that I, FRED A. DENNETT, a citizen of the United States of America, residing at Sheboygan, in the county of Sheboygan and 5 State of Wisconsin, have invented and produced a certain new, useful, and original Design for an Article of Manufacture—to wit, a Veneer-Pressing Member—of which the following is a specification, reference being had to the accompanying drawings, forming a part thereof.

In said drawings, Figure 1 is a plan view of a veneer-pressing member embodying my design. Figs. 2 and 3 are views in cross-section of the same, taken on lines 2 2 and 3 3, respectively, in Fig. 1. Figs. 4 and 5 are longitudinal sectional views taken on lines 4 4 and 5 5, respectively, in Fig. 1, these five views being deemed necessary for full illustration.

The leading and essential feature of my design of a veneer-pressing member consists of the peculiar and novel formation of the depressed portion of the upper surface of the same. The upper surface between the points *a*, *b*, *c*, and *d* is rectangular in form, and aside from the depressed portion before referred to is in one plane. The rear edge of the depressed portion between the points *ff* takes 25 the form of a semicircle, and from each point *f* to the points *e* each edge of the depression proceeds on a straight line parallel with the sides *a c* and *b d*. The edge of the depression between the points *ee* is indefinite, but 30 substantially straight and parallel with the side *c d*. The inward slope of the depressed portion from the semicircular line *ff* and the

straight lines *ef* is rather abrupt, as shown in Figs. 2 and 3. From the center of the forward end of the depressed portion a mound 40 proceeds back toward the semicircular line and gradually sinks to the lowest level of said depressed portion on an irregular curve, as shown at *g* in Fig. 4, slightly in the rear of a straight line taken between the points *ff*. 45 The sides of said mound slope in either direction toward the depressed portions shown in Fig. 3. From an indefinite straight line between the points *ee*, aside from the portion taken up by said mound, the slopes of the depression proceed from said indefinite line *ee* to the lowest portion of said depression more gradually than the slope from the semicircular edge and the lines between the points *ef*.

The several minor features of my design of 50 a veneer-pressing member may be stated as follows: The bottom of said veneer-pressing member is flat, and its plane is parallel with the plane of the upper surface of said member, aside from the depressed portion. The 55 sides are parallel planes and stand at right angles with the upper surface and the bottom, as do the ends.

Having thus described my design, what I 60 claim is—

The design of a veneer-pressing member, 65 substantially as shown and described.

Signed by me at Milwaukee, Wisconsin, this 22d day of November, A. D. 1900.

FRED A. DENNETT.
